Antonia Campi, Laveno Mombello, Varese, Italy, assignor
to Societa Ceramica Italiana Societa per Azioni Laveno, Varese, Italy

Filed Dec. 30, 1964, Ser. No. 83,227

Claims priority, application Italy Nov. 17, 1964

Term of patent 14 years

(Cl. D44—15)

Fig.1

Fig.3

FIG. 1 is a top plan view of a dinner plate or similar article showing my new design, it being understood that the pattern disclosed is continuous about the entire periphery in the path included within the broken lines;

I claim:

The ornamental design for a dinner plate or similar article, as shown and described.
